PADLOCK

John P. J. Vickers, Dartmouth, Nova Scotia,
Canada

Application September 5, 1947, Serial No. 772,251

1 Claim. (Cl. 70—38)

1
My invention relates to improvements in padlocks.

An important object of the invention is to provide a padlock having means for locking a plurality of articles simultaneously.

A further object of the invention is to provide a padlock having novel means to eliminate the possibility of closing the lock shackle, while the same is out of registration with the shackle opening.

A further object is to provide a lock which is convenient to use in the dark, because the lock shackle cannot be closed without properly engaging within the shackle opening.

A further object is to provide a padlock having a seamless cylindrical body, well adapted to be made from metal tubing.

A still further object is to provide a superior padlock of simple and durable design, which may be manufactured as cheaply as other conventional types of padlocks.

Other objects and advantages of the invention will be apparent during the course of the following description.

In the accompanying drawings, forming a part of this application, and in which like numerals are employed to designate like parts throughout the same,

Figure 1 is a side elevation of a padlock embodying the invention.

Figure 2 is a plan view of the same.

Figure 3 is a central vertical section taken on line 3—3 of Figure 2, parts in elevation.

Figure 4 is a similar section showing the shackle in the open or unlocked position.

Figure 5 is a horizontal section taken on line 5—5 of Figure 3, and

Figure 6 is a plan view showing a modification of the invention.

In the drawings, where for the purpose of illustration are shown preferred embodiments of the invention, attention is called first to Figures 1 to 5, inclusive, wherein the numeral 10 designates the casing or body of the padlock. This casing 10 is preferably cylindrical, and well adapted to be made from metal tubing, or bar stock. The body or casing 10 has a central axial bore 11 formed in its bottom end, and this bore 11 leads into a reduced cylindrical bore 12, forming an annular shoulder or seat 13. The top of the casing is recessed to provide an annular groove 14. Also formed in the bottom of the casing and spaced radially outwardly from the central bore 11, is a longitudinal cylindrical recess or bore 15, within which is rigidly mounted

2
a conventional key controlled lock operating mechanism 16. The bore 15 extends longitudinally of the casing 10, parallel to the bore 11, and terminates near the longitudinal center of the casing.

The key controlled lock operating mechanism 16 includes an outer cylindrical barrel 17, rigidly mounted within the bore 15, and a plunger 18, rotatably mounted within the barrel. The plunger 18 is turned upon its horizontal axis by a suitable key 19, received in a longitudinal key opening in the plunger. The key operates tumblers within the plunger, and not shown on the drawing, to rotate said plunger. This is a conventional lock operating mechanism, as stated. The plunger 18 includes an inner shoulder or disc 20, having rigidly mounted thereon, at one side of the same, an upstanding projection or pin 21. This pin 21 projects into an opening 22, forming an innermost portion of the bore 15 and having a straight side 23, forming a lateral shoulder. When the plunger 18 is turned by the key, the pin 21 will turn with it and move from the position shown in Figure 5, toward the shoulder 23.

Slideably mounted within a radial recess or opening 24, and disposed above the opening 22 is a bolt or keeper 25. This keeper has a lower transverse projection 26, extending into the opening 22, and adapted to be engaged by the pin 21 for moving the keeper. The keeper recess 24 and keeper 25 have their longitudinal axes arranged at right angles to the axis of the bore 15, and the inner end of the recess 24 leads into the casing bore 12. The outer end of the radial recess 24 terminates near the outside of the casing 10. An expandable coil spring is disposed within the outer portion of the recess 24, and engages against the outer end of the keeper 25 to urge the same radially inwardly.

Slideably mounted within the bore 12 is the center longitudinal stem or shank 28 of a lock shackle 29. The shackle 29 includes a plurality of, and preferably three shackle arms 30, which are preferably equidistantly angularly spaced, see Figure 2. These arms 30 are joined at their inner ends to the shank 28, and are integral therewith. The outer longitudinal portions 30' of the shackle arms are adjacent to the annular groove 14, and adapted to enter the same when the lock shackle is closed, Figure 3. The shank 28 has an annular groove 31 near its longitudinal center, to receive the inner end of the keeper 25 when the shackle 29 is closed. The shank 28 extends into the bore 11, and carries an end disc or head 32, to engage

the annular shoulder 13 to limit the opening movement of the shackle, Figure 4. An end plate 33 is rigidly mounted within the outer end of the bore 11, and flush with the bottom of the casing 10. An expandible coil spring 34 is mounted upon the end plate 33, and engages the head 32 to urge the shackle 29 upwardly toward its open position.

In use, one or more articles may be locked under the arms 30. When it is desired to open the lock, the key 19 is turned, turning the plunger 18 and pin 21. The pin 21 pushes the projection 26 and keeper 25 to the right, in Figure 3, and the keeper moves out of the groove 31. When this occurs, the shackle 29 snaps upwardly to its open position, Figure 4. If the key is turned while the shackle 29 is open, so that the spring 27 can move the keeper inwardly against the shank 28, the keeper will automatically enter the groove 31, when the shackle is again closed. The shackle 29 may be turned upon its longitudinal axis, but the shackle arms 30 cannot move out of registration with the groove 14. The lock will, therefore, properly close any time the shackle is pushed inwardly.

In Figure 6, there is illustrated a modified form of the invention, wherein individual shackle arm receiving openings 14a are formed in the top of the casing 10, instead of the annular groove 14, of the first form of the invention. All other parts and their functions, in this form of the invention are identical with those shown and described in connection with the first form thereof. In Figure 6, the arms 30 must enter the openings 14a to close the lock, and the lock cannot be closed until the arms 30 register with the openings 14a.

It is to be understood that the forms of my invention herewith shown and described are to be taken as preferred examples of the same, and that various changes in the shape, size and arrangement of parts may be resorted to, without departing from the spirit of my invention or the scope of the subjoined claim.

Having thus described my invention, what I claim is:

A padlock, comprising a cylindrical body having a central axial bore including an enlarged bottom portion forming a shoulder and an annular groove

in one end surrounding the bore and substantially concentric therewith, an axially shiftable shackle shank mounted within the central axial bore and provided near its inner end with a head, said head being disposed within the enlarged portion of the bore and adapted to engage the shoulder to limit the outward movement of the shackle shank, the shackle shank being provided between its ends with an annular groove, a spring disposed within the central axial bore inwardly of the shackle shank and engaging the inner end of the shank to urge it outwardly toward its open position, a plurality of angularly spaced radial arms secured to the outer end of the shackle shank and having parts to engage in the annular groove of the body when the shackle shank is shifted inwardly to its closed position, the shackle shank being turnable upon its longitudinal axis in the open and closed position, the cylindrical body having a radial passage between its ends and leading into the central axial bore and an axial opening parallel to the central axial bore and spaced radially outwardly therefrom and leading into the radial passage, a bolt mounted within the radial passage and having a lateral extension projecting into the axial opening, a spring within the radial passage and behind the bolt to urge the bolt into the annular groove of the shackle shank, and a key operated plunger mounted within the axial opening and rotatable upon its longitudinal axis and having an eccentric element at its inner end adjacent to the lateral extension of the bolt, the eccentric element engaging the lateral extension when the key operated plunger is turned for shifting the bolt out of the annular groove of the shackle shank.

JOHN P. J. VICKERS.
